Attorney.

UNITED STATES PATENT OFFICE.

NICKLAS BAUER, OF SPRINGFIELD, OHIO.

EXTENSION-TABLE.

SPECIFICATION forming part of Letters Patent No. 257,274, dated May 2, 1882

Application filed November 25, 1881. (No model.)

To all whom it may concern:

Be it known that I, NICKLAS BAUER, a citizen of the United States of America, residing at Springfield, in the county of Clarke and State of Ohio, have invented certain new and useful Improvements in Extension-Tables; and I do hereby declare the following to be a full, clear, and exact description of my invention, such as will enable others skilled in the art to 10 which it appertains to make and use the same, reference being had to the accompanying drawings and letters or figures of reference marked thereon, which form a part of this specification, and in which—

15 Figure 1 is a perspective view of the two slide-bars, one above the other. Fig. 2 is a longitudinal vertical section taken on the line $x\ x$ of Fig. 3. Fig. 3 is a vertical cross section taken on the line $y\ y$ of Fig. 2, and Fig. 4 is a 20 vertical cross-section taken upon the line $z\ z$ of Fig. 2.

My invention relates more particularly to the sliding bars of an extension-table, and has for its object a spring device to hold the slide-bars together and take up any loss in wear; and it consists in the construction and arrangement of parts hereinafter more fully set forth.

In the accompanying drawings, A and B represent slide-bars used in the construction of an 30 extension-table, provided with mortises C and D, with receding sides. These mortises, at their upper ends, are provided with flaring tenons E and F, of peculiar construction.

The tenons are preferably constructed of 35 hickory wood or other suitable elastic material, and have their bases constructed of the

required form to fit the mortise of the sliding bar in which they are secured and their tops flared so as to fit and slide easily in the opposing slide-bar. Before these tenons or 40 “tongues,” as they may be called, are secured in the mortise they are cut by a saw upon the line shown at G in Figs. 1, 2, and 4 of the drawings, making an opening from near the center of the end across the tenons on a horizontal 45 line, extending a short distance, then curving upward and backward a suitable distance, where it ends, thus forming a spring, H.

When placed in the mortise a screw, I, is driven through the spring H a suitable distance in front of the end of the saw-cut and 50 through the tenon into the bar, drawing the spring down as far as may be required for the requisite amount of pressure against the receding sides of the mortise in which it travels.

Having thus described my invention, I desire to claim and secure by Letters Patent—

An elastic tenon or tongue for the slide-bars of an extension-table, constructed of a single piece of hickory or other suitable material, provided with a spring, H, said spring being constructed by a saw-cut, G, extending across the tongue near its narrowest point and backward from one end a suitable distance, and held down by a screw, I, substantially as shown and 65 described.

In testimony whereof I affix my signature in presence of two witnesses.

NICKLAS BAUER.
